UNITED STATES PATENT OFFICE.

CARL AUGUST PFENNING, OF BARMEN - RITTERSHAUSEN, PRUSSIA,
GERMANY.

BUTTON.

SPECIFICATION forming part of Letters Patent No. 351,792, dated November 2, 1886.

Application filed July 19, 1886. Serial No. 208,381. (No model.)

To all whom it may concern:

Be it known that I, CARL AUGUST PFENNING, a subject of the Emperor of Germany, residing at Barmen - Rittershausen, Rhenish 5 Prussia, Germany, have invented a new and useful Improvement in Buttons, of which the following is a specification.

This invention relates to flexible-stuff shanks for buttons; and its object is a shank for buttons which shall be simple in construction and of which the several parts shall be firmly fixed together.

This improved button-shank is shown in the accompanying drawings, in which Figures 1, 15 2, and 3 show in section the three parts of which my improved shank is built up; Figs. 4 and 5, the shank in various stages of manufacture; Fig. 6, the finished shank. Figs. 7 and 8 show the after process by which it may 20 be converted into a finished button.

Like reference - letters show similar parts throughout the figures.

Into a cylindrical ring, *c*, of metal, the upper rim of which is bent outward, as shown in 25 Fig. 1, is introduced, in the manner shown in Fig. 4, a circular piece, *l*, of stuff or cloth, which serves for the flexible-stuff shank, or that part of the button by which it may be 30 sewed to the garment. The edge of this piece of cloth is allowed to project slightly over the inclined rim of the ring *c*, and a circular metal cap, *k*, Fig. 3, provided with a downwardly-projecting flange, is placed over the same and said flange bent down inwardly, as shown in

Fig. 6, so as to clip the said edge of the cloth 35 piece *l* between the flange and the outwardly-projecting rim of the ring *c*, and thus hold the cloth edge securely in place. The shank is now complete, and appears as shown in section in Fig. 6.

This shank will form the basis of the finished button, which can be made as follows: The inner back piece, *a*, is placed as shown in Fig. 7, and a second cap, *b*, forming a stretcher for the cloth for the surface of the button, is 45 then placed over the front and its flange bent down over the rim of the inner back piece, *a*. The surface cloth *s* is then stretched over the cap *b* and secured behind by the outer back plate, *m*, which, lastly, is itself secured in place 50 by bending outwardly over it the lower rim of the inner cylindrical ring, *c*, as shown in Fig. 8.

What I claim as my invention, and desire to secure by Letters Patent of the United States, 55 is—

The shank for buttons, consisting of the cylindrical ring *c*, with its upper rim bent outward, the stuff piece *l*, and the flanged cap *k*, the whole combined substantially as described 60 and illustrated.

In testimony whereof I have signed this specification in the presence of two subscribing witnesses.

CARL AUGUST PFENNING.
